UNITED STATES PATENT OFFICE.

MARCELLUS F. COWDERY, OF SANDUSKY, OHIO.

IMPROVEMENT IN BLACKBOARDS.

Specification forming part of Letters Patent No. 123,456, dated February 6, 1872.

SPECIFICATION.

Be it known that I, MARCELLUS F. COWDERY, of city of Sandusky, county of Erie, State of Ohio, have invented an Improvement in the Preparation of Blackboards for school purposes; and I declare the following to be a full, clear, and exact description of same, such as will enable others skilled in the art to which it pertains to make and use it, reference being had to the accompanying drawing forming part of these specifications.

My invention relates to the manner of preparing the paper fabric for the application of the blackboard composition. My invention consists in treating to a thorough coating of boiled oil the paper fabric which forms the body of the blackboard, to render the same impervious to moisture, and thereby prevent its warping or becoming harsh, and consequently cracking and becoming worthless.

After the paper has been thus prepared I finish it on both sides with any of the ordinary blackboard compositions.

In the drawing, Figure 1 represents a blackboard, both sides of which are finished similarly; also, a section along the line X Y, in which—

b is the fabric, which has been treated with boiled oil, and *a a* are the coatings of blackboard compositions.

Having thus described my invention, what I claim as new, and desire to secure by Letters Patent, is—

The blackboard, when the paper fabric of which it is composed is previously treated with boiled oil, as and for the purposes herein described.
